UNITED STATES PATENT OFFICE.

REUBEN S. CORMIER, OF NEW BEDFORD, MASSACHUSETTS.

PICTURE-SUSPENSION BAR.

1,035,319.

Specification of Letters Patent. Patented Aug. 13, 1912.

Application filed September 17, 1910. Serial No. 582,586.

To all whom it may concern:

Be it known that I, REUBEN S. CORMIER, of New Bedford, in the county of Bristol and State of Massachusetts, a citizen of the 5 United States of America, have invented a new and useful Picture-Suspension Bar for Hanging and Suspending Pictures and Mirrors, of which the following is a specification.

10 My invention relates to improvements in picture suspension bars and has particular reference to a device for hanging or suspending mirrors, pictures and the like without the use of wire, cord, string or like 15 means.

My invention has for its object the provision of a device of the character described which will be capable of hanging and retaining pictures, mirrors and the like, in- 20 dependent of wire, cord or string.

Other objects of my invention are the provision of a device of this kind which will be extremely simple in construction and inexpensive of production and which will ef- 25 fectually secure the picture or mirror in position upon the wall.

To attain the desired objects my invention consists of a picture suspension bar of the character and for the purpose stated em- 30 bodying novel features of construction and combination of parts for service sub- substantially as disclosed herein.

Figure 1 represents a side elevation of my hanger applied to the molding and 35 frame to illustrate the manner of using the device. Fig. 2 represents a front elevation of the picture hanger, and Fig. 3 represents a detail view of the portion of my device which is connected to the frame.

40 In carrying my invention into effect I employ a strip of material formed at its upper end with the hook C to engage the usual picture rail, thence with the angular down and inwardly extending portion B 45 and from said portion B extends the main vertical portion A, at its lower portion formed with the large curved loop D, which at its upper end terminates in the right- angled portion G, the inclined terminal of 50 which is formed with an eye or opening H to

receive a screw or fastening for connecting the device with the picture frame.

It will be observed that the device in its entirety is secured to the picture frame in a rigid and vertical position with reference to 55 the picture frame, and that the loop and right-angled terminal give the proper angle to the picture and that the vertical main bar rests upon the wall forming a broad, long, firm support and brings the suspen- 60 sion hook in the exact place to engage the usual rail.

By means of my hanger, the picture can be instantly hung in the proper place and cannot possibly change its position, but can 65 be quickly removed when desired; also the picture can be supplied with my hanger applied at the smallest fraction of cost and save a great amount of trouble in hanging; also the single article takes the place of 70 screws, cords and hangers now used and provides a more simple, inexpensive and practical substitute.

I claim:

1. A picture hanging device, consisting of 75 a single piece of metal having a hook at one end to engage the picture rail, a main vertical bar to rest flat against the wall to support the frame, a wide curved loop to give the proper position to the frame, and 80 a portion bent at right angles to the loop part and terminating in an attaching member or eye at right angles to the said portion for connection with the frame.

2. A picture hanging device, consisting of 85 a piece of metal having a hook at its upper end to engage the picture rail, an intermediate vertical portion to rest flat against the wall to form a support, a wide curved loop having a portion bent at right angles to 90 the outer side of the loop and terminating in an attaching member or eye adapted to receive a fastening to connect the hanger to the frame, the shape of the loop giving to the connecting terminal the proper inclina- 95 tion to hang the picture at the desired angle.

REUBEN S. CORMIER.
